(57) **CLAIM**

I claim the ornamental design for a portable case for battery charger or power adaptor, as shown and described.

DESCRIPTION

FIG. 1 is a top, front perspective view of a portable case for battery charger or power adaptor;

FIG. 2 is a bottom view of the portable case for battery charger or power adaptor;

FIG. 3 is a top view of the portable case for battery charger or power adaptor;

FIG. 4 is a left side view of the portable case for battery charger or power adaptor;

FIG. 5 is a right side view of the portable case for battery charger or power adaptor;

FIG. 6 is a front view of the portable case for battery charger or power adaptor; and,

FIG. 7 is a rear view of the portable case for battery charger or power adaptor.

The broken lines in the figures depict portions of the portable case for battery charger or power adaptor which form no part of the claimed design.
